CLAIM

The ornamental design for a camera lens, as shown and described.

DESCRIPTION

FIG. 1 is a perspective view of a camera lens showing my new design;

FIG. 2 is a front view thereof;

FIG. 3 is a rear view thereof;

FIG. 4 is a top plan view thereof;

FIG. 5 is a bottom plan view thereof;

FIG. 6 is an enlarged right side view thereof;

FIG. 7 is an enlarged left side view thereof;

FIG. 8 is an enlarged perspective view taken from indication 8 of FIG. 1;

FIG. 9 is an enlarged elevation view taken from indication 9 of FIG. 2;

FIG. 10 is a cross-sectional view taken along line 10-10 in FIG. 9;

FIG. 11 is a cross-section view taken along line 11-11 in FIG. 9;

FIG. 12 is a perspective view of FIG. 8 showing the state in which the lever is in a locked position;

FIG. 13 is an elevation view of FIG. 9 showing the state in which the lever is in a locked position; and,

FIG. 14 is an elevation view taken from indication 9 of FIG. 2 showing the state in which the lever is in an unlocked position.

(Continued)

The dot-dash-dot broken lines in the drawings define the bounds of the claim and form no part thereof.

1 Claim, 14 Drawing Sheets
